UNITED STATES PATENT OFFICE.

FREDRICK C. MILLER, OF NEWPORT, KENTUCKY.

DESIGN FOR A BOX-OPENER.

SPECIFICATION forming part of Design No. 16,604, dated April 6, 1886.

Application filed February 15, 1886. Serial No. 192,041. Term of patent 14 years.

To all whom it may concern:

Be it known that I, FREDRICK C. MILLER, a citizen of the United States, of Newport, in the county of Campbell and State of Kentucky, have invented and produced a new and original Design for Box-Openers, of which the following is a specification, reference being had to the accompanying drawings, forming part thereof.

10 Figure I is a perspective view of my newly-designed box-opener. Fig. II is a side view of the same; Fig. III, a transverse section on the line III III, Fig. II. Fig. IV is a transverse section through the handle at IV IV, Fig. II. Fig. V is a transverse section through the blade at V V, Fig. II.

15 Figs. II, III, IV, and V show accurately the contour of the box-opener. It will be seen to consist of a body, 1, having a handle, 2, slightly

oval in cross-section, and a flat blade, 3, with 20 a round end, in which blade is formed a beveled nick, 4, and on the opposite side a boss, 5, merging into the body by symmetrical curves on all sides, and having a nearly circular flat face.

25 The following is what I claim as new in my design and desire to secure by Letters Patent:

The design for a box-opener herein shown and described, the same consisting of an ovate 30 handle, 2, with a flat blade, 3, and a circular boss, 5, of greater thickness than the blade, merging thereinto by regular curves, as set forth.

FREDRICK C. MILLER.
